UNITED STATES PATENT OFFICE.

JAMES T. PHILLIPS, OF GRAND RAPIDS, MICHIGAN, ASSIGNOR TO THE ALDINE MANUFACTURING COMPANY, OF SAME PLACE.

DESIGN FOR A FRAME FOR GRATES.

SPECIFICATION forming part of Design No. 22,634, dated July 18, 1893.

Application filed March 10, 1893. Serial No. 465,430. Term of patent 7 years.

To all whom it may concern:

Be it known that I, JAMES T. PHILLIPS, of Grand Rapids, Kent county, State of Michigan, have invented and produced a new and original Design for Grate-Frames, of which the following is a specification.

In the drawings, Figure 1 is a front view, and Fig. 2, a profile view of a grate showing my design.

10 The leading feature of my design is in the surface ornamentation of the grate facings, or frame surrounding the grate opening.

15 In the drawings the grate opening is shown at *a*, with the grate at *b*, and below the grate bars the opening is closed by an ornamental

plate *c*. Surrounding the opening *a* of uniform width is a frame work *d*, or facing and this is ornamented by conventional leaf shaped scrolls. Across the grate bars ornamental scrolls extend from a center piece. 20

What I claim is—

The design for grate frames herein shown and described.

In testimony whereof I affix my signature in presence of two witnesses.

JAMES T. PHILLIPS.

Witnesses:

CHAS. M. WILSON,
JOHN E. MORE.
